UNITED STATES PATENT OFFICE.

TITO LIVIO CARBONE, OF GRUNEWALD, NEAR BERLIN, GERMANY.

ELECTRIC-ARC LAMP.

SPECIFICATION forming part of Letters Patent No. 737,342, dated August 25, 1903.

Application filed December 30, 1902. Serial No. 137,186. (No model.)

To all whom it may concern:

Be it known that I, TITO LIVIO CARBONE, a subject of the King of Italy, residing at Grunewald, near Berlin, in the Kingdom of Prussia, German Empire, have invented certain new and useful Improvements in Arc-Lamps; and I do hereby declare that the following is a full, clear, and exact description of the invention.

10 In a separate application filed March 25, 1903, Serial No. 149,583, a similar invention is disclosed; but the subject-matter of the said application is not claimed specifically herein.

15 The present invention relates to means for influencing magnetically the arc of electric-arc lamps in order to obtain a very bright, steady, and white light, while the carbons burn up without residues. The magnetic-effect may be obtained most simply by arranging an iron ring close to and above the arc, the ring being transversed by lines of magnetic induction produced by a coil, the lines being led to and from said ring by means of two iron rods and passing between two opposite points of the ring. The lines of force coming from the north pole are thus divided and pass to the south pole through the two halves of the ring. An auxiliary iron rod is used so that the magnetically-influenced arc 25 is exactly in the center of the iron ring. The auxiliary iron rod may project as an angle-arm from the one iron rod and may reach close to the connection-point of the ring with the other iron rod, or the auxiliary iron rod 30 may be arranged vertically movable on the one side of the coil, so that it may be adjusted higher or lower, as desired.

Instead of using the auxiliary iron rod, a coil may be arranged horizontally movable 40 on its iron core, so that the magnetically-influenced arc is exactly in the center of the iron ring.

The subject of the present invention is diagrammatically represented in the annexed drawings.

45 It is understood that the arc passes between two pairs of carbons, meeting one another at an acute angle, though my invention is not limited to this arrangement of the carbons. 50 Both carbon rods of each carbon pair face one another with their flat sides and touch one another only at their lower ends where the arc

is formed, because the two rods are inclined together at an acute angle.

The guiding and feeding of the carbons in 55 the above mechanism may be automatically effected in any known or suitable manner.

Figure 1 shows a device in which the auxiliary iron rod projects as an angle-arm from one iron rod. Fig. 2 shows the two pairs of 60 carbon rods in plan view. Fig. 3 is a device in which the auxiliary iron rod is vertically movable on one side of the coil. Fig. 4 shows a device in which the coil can be moved horizontally on its iron core. 65

A little above the place where the arc is to be formed the ring *a* is arranged. It is carried by two iron rods *b* and *c*, which are connected to the coil *d* in such a way that the lines of induction produced by the coil when 70 a current passes may reach the ring *a* and return from the latter to the coil.

In the device shown in Fig. 1 the angle-arm *e*, serving as an auxiliary iron rod, projects from the rod *b* and terminates near to the connection-place of the ring *a* at the lower end of the iron rod *c*. The angle-arm *e* can be adjusted higher or lower within a slot *b'* and may be clamped, by means of the nut *b''*, at that height where the magnetically-influenced 75 arc is exactly in the center of the iron ring *a*, which may easily be found by experiment.

In the device shown in Fig. 3 the auxiliary iron rod *f* is movable on the one side of the coil within a socket *g* and can be clamped at 80 the desired height by means of a set-screw *h*, so that the arc is exactly in the center of the ring *a*.

In the device shown in Fig. 4 the coil *d*, wound on a spool *k*, is horizontally movable 90 with respect to its iron core and can be adjusted in the desired position between the two iron rods *b* *c* by means of the screw *i* in such a manner that the arc is exactly in the center of the ring *a*. 95

Having now described my invention and in what manner the same is to be performed, what I claim, and desire to secure by Letters Patent, is—

1. In arc-lamps, the combination with the 100 carbons of an electromagnet, iron rods secured to opposite poles of said magnet, and an iron ring surrounding the carbons above the arc and carried by said rods at diamet-

rically opposite points, substantially as described.

2. In arc-lamps, the combination with the carbons of an electromagnet, iron rods secured to opposite poles of said magnet, an iron ring surrounding the carbons above the arc and carried by said rods at diametrically opposite points, and adjusting means for maintaining the arc in a definite position in relation to the magnet connections, substantially as described.

3. In arc-lamps, the combination with the carbons of an electromagnet, iron rods se-

cured to opposite poles of said magnet, an iron ring surrounding the carbons above the arc and carried by said rods at diametrically opposite points, and a vertically-movable iron rod for adjusting the arc in a definite position in relation to the magnet connections, substantially as described.

In witness whereof I have hereunto set my hand in presence of two witnesses.

TITO LIVIO CARBONE.
